UNITED STATES PATENT OFFICE.

JOHN C. CAIRNS, OF SOMERVILLE, MASSACHUSETTS.

GAME APPARATUS.

SPECIFICATION forming part of Letters Patent No. 771,895, dated October 11, 1904.

Application filed June 10, 1904. Serial No. 211,972. (No model.)

To all whom it may concern.:

Be it known that I, JOHN C. CAIRNS, a citizen of the United States, residing in Somerville, in the county of Middlesex and State of 5 Massachusetts, have invented certain new and useful Improvements in Game Apparatus, of which the following is a specification.

This is a game apparatus adapted for indoor or outdoor use and to be suspended from the 10 opposite walls of a room or from a pair of standards or posts; and it comprises a netting divided into two courts, end frames, a central frame between the courts and provided with a substantially horizontal trough, side cords 15 extending from the end frames to the trough, cross-cords over each court, and supporting-cords.

In playing the game a ball which rests on the netting in one court is struck from the 20 under side through the mesh by means of a mallet, and is thereby knocked up over one cross-cord after another until it is finally landed in the trough.

The nature of the invention is fully described in detail below and illustrated in the 25 accompanying drawings, in which—

Figure 1 is a perspective view of my game apparatus in position for use. Fig. 2 is a view of the pick or mallet which is employed in 30 striking the ball. Fig. 3 is an enlarged longitudinal vertical section in detail, illustrating the position of the pick when striking the ball and the course of the ball while the game is being played.

35 Similar letters of reference indicate corresponding parts.

In this apparatus there are three upright frames, a central frame and two end frames. Each end frame consists of two vertical posts 40 *a*, an upper cross-bar *b*, and a lower cross-bar *c*. The central frame consists of two upright posts *d*, a lower cross-bar *e*, and a trough *g*, said trough consisting of two side walls inclined toward each other, as shown, and preferably without any bottom. This trough is of suitable width to sustain a ball *f* on its upper edges and prevent it from dropping through. A netting *h* extends from one cross-bar *c* over the cross-bar *e* to the other cross-bar *c*, and the mesh of this netting is large 45

enough to retain the ball within one of its open squares and prevent it from rolling, but not sufficiently large to allow the ball to drop through.

To each post *a* in one end frame there is secured a cord or rope *k*, which extends to an eye *l* on the upper end of the post *d* on that side and is secured to the said eye in any suitable manner and thence extends and is secured to the corresponding post *a* of the 55 other end frame. By the above-described construction the device is divided into two courts or fields on opposite sides of an imaginary line drawn transversely across the netting directly under the trough *g*, and over each 60 court there are horizontal cross-cords *n*, preferably three in number, extending from one cord *k* to the other and parallel with each other and with the trough *g* and cross-bar *b*.

The device is sustained and suspended at the 65 desired height—say approximately the height of the shoulders of the players—by means of three cords at each end—namely, the cord *p*, which extends from the central portion of the cross-bar *c* to an eye *r*, and the two cords *s*, 70 which extend from the upper portions of the posts *a* to said eye in line with the cords *u*, extending from the upper portions of the posts *a* to the lower portions of the posts *d*, the eye itself being caught over a suitable hook 75 *m* on any suitable post, as *t*, or the hook may be secured to any suitable wall or support. These cords are of suitable length to lift the frame *d* a little in order that there may be a slight upgrade from the cross-bars *c* to the 80 cross-bar *e*. This is for the purpose of preventing the ball during play from rolling toward the central frame.

v represents the head, and *w* the handle, of a picker or striking-mallet.

In operation, the ball *f* having been placed on the netting near one end, the player at that end takes the picker and holds it under the netting and strikes the ball from the under side, swinging the picker upward and striking 95 the ball through the mesh, with the object of sending the ball over the first cross-cord *n* and allowing it to drop to the netting in the same court between said cross-cord and the next one. This is continued in the manner 100

illustrated by dotted lines in Fig. 3 until the ball has jumped the last cross-cord and landed in the trough *g*. The last stroke may be over the last cross-cord into the trough or from the 5 space between the last cross-cord and the central frame into the trough. The players take turns in the endeavor to jump the cross-cords successively and land the ball in the trough with the fewest number of strokes.

10 The apparatus may be placed at any desired height which is most convenient for making the upward-swinging strokes of the pick.

Having thus fully described my invention, what I claim, and desire to secure by Letters 15 Patent, is—

1. In a game apparatus of the character described, a central trough and a frame supporting the trough; upright end frames on opposite sides of the trough; netting connecting 20 the lower portions of the trough-frame and the two end frames; cords or ropes connecting the upper portions of the end frames with the trough; and means for supporting the apparatus in a raised position, for the purpose 25 set forth.

2. In a game apparatus of the character described, a central trough, and a vertical frame supporting the trough; upright end frames on opposite sides of the trough; netting connecting 30 the lower portions of the trough-frame

and the end frames; cords or ropes connecting the upper portions of the end frames with the trough; cross-cords connecting the said cords or ropes between the trough and the opposite end frames; and means for supporting the 35 apparatus in a raised position, for the purpose set forth.

3. The herein-described improved game apparatus, comprising the flaring trough *g*; the central supporting-frame *d, e*; the end frames 40 *a, b, c*; a netting connecting the lower portions of the trough-frame and the two end frames; the cords or ropes *h* connecting the outer ends of the end frames and the trough; the cross-cords *n* supported by the cords *k* on opposite 45 sides of the trough; the lifting-cords *u* extending from the lower portion of the central frame to the upper portions of the end frames; the supporting-cords *s* extending outward from the upper portions of the end frames; 50 and the supporting-cords *p* extending outward from the lower portions of the end frames, for the purpose set forth.

In testimony whereof I have signed my name to this specification in the presence of two sub- 55 scribing witnesses.

JOHN C. CAIRNS.
